(57) **CLAIM**

The ornamental design for a hose coupling set, as shown and described.

DESCRIPTION

FIG. 1 is a top, front, right-side, perspective view of a female hose coupling of the hose coupling set of my design; FIG. 2 is a front view of the female hose coupling shown in FIG. 1;

FIG. 3 is an exploded view of the female hose coupling shown in FIGS. 1-2;

FIG. 4 is a side view of the nut portion of the female hose coupling shown in FIGS. 1-3;

FIG. 5 is a top, partial cross-sectional view of the nut portion of the female hose coupling shown in FIGS. 1-4, taken along line 5-5 shown in FIG. 4, and rotated 90° clockwise relative to the direction-of-sight;

FIG. 6 is a close-up view of the nut section “FIG. 6” shown in FIG. 5;

FIG. 7 is a front, top, right-side perspective view of a male hose coupling of the set of my design;

FIG. 8 is a front view of the male hose coupling shown in FIG. 7;

FIG. 9 is a top, partial cross-sectional view of the male hose coupling shown in FIGS. 7 and 8, taken along 9-9 shown in FIG. 8;

FIG. 10 is a cross-sectional view of the male hose coupling shown in FIGS. 7-9, taken along line 10-10 shown in FIG. 9;

FIG. 11 is a close-up view of section “FIG. 11” shown in FIG. 9; and,

FIG. 12 is an elevation view of my design of a hose coupling set.

The dash-dash broken lines shown in the figures are for the purpose of illustrating portions of the environment and form no part of the claimed design.
